CLAIM

The ornamental design for a skylight guard, as shown and described.

DESCRIPTION

FIG. 1 is a front, top perspective drawing of one embodiment of a skylight guard showing our new design;

FIG. 2 is a right side view thereof;

FIG. 3 is a left side view thereof;

FIG. 4 is a front view thereof;

FIG. 5 is a back view thereof;

FIG. 6 is top view thereof;

FIG. 7 is a bottom view thereof;

FIG. 8 is a front, top perspective view of a second embodiment thereof;

FIG. 9 is a right side view of the second embodiment thereof;

FIG. 10 is a left side view of the second embodiment thereof;

FIG. 11 is a front view of the second embodiment thereof;

FIG. 12 is a back view of the second embodiment thereof;

FIG. 13 is a top view of the second embodiment thereof;

and,

FIG. 14 is a bottom view of the second embodiment thereof.
